GUN SIGHT

Robert Korzeniewski, 115 N. Live Oak St.,
Carthage, Tex. 75633

Filed Sept. 6, 1973, Ser. No. 394,911

Term of patent 14 years

Int. Cl. D16—06; D22—99
U.S. Cl. D22—8

FIG. 1

FIG. 2

FIG. 3

FIG. 4

FIG. 5

FIG. 6

FIG. 1 is a perspective view of a gun sight;
FIG. 2 is a top view;

FIG. 3 is a right side elevation view. The left side elevation view is substantially the same as the right side elevation view;

FIG. 4 is a bottom view;

FIG. 5 is a rear end view; and

FIG. 6 is a front end view.

I claim:

The ornamental design for a gun sight, substantially as shown and described.
